Primary Examiner — John Windmuller*Assistant Examiner* — Steven Czyz(74) *Attorney, Agent, or Firm* — Luedeka Neely Group PC(57) **CLAIM**

The ornamental design of a circular table, as shown and described.

DESCRIPTION

FIG. 1 is a top perspective view of the circular table;

FIG. 2 is a side plan view of the circular table;

FIG. 3 is an end plan view of the circular table;

FIG. 4 is a top plan view of the circular table;

FIG. 5 is a bottom plan view of the circular table; and,

FIG. 6 is a bottom perspective view of the circular table. The broken lines shown in the figures are included for the purpose of illustrating environment only and form no part of the claimed design.

1 Claim, 6 Drawing Sheets(56)
